GRIPPER MECHANISM

Joseph Fossa, Hamilton, Mass., assignor to United
Shoe Machinery Corporation, Flemington, N. J.,
a corporation of New Jersey

Application February 26, 1947, Serial No. 730,978

14 Claims. (Cl. 12—1)

1

This invention relates to gripper mechanism and the herein illustrated embodiment thereof is shown applied to a lasting machine of the type disclosed in United States Letters Patent No. 2,411,827, issued in my name on November 26, 1946. It will be understood, however, that the novel gripper mechanism of this invention is not limited in its utility to use in a lasting machine or to application to a lasting machine of the exact construction exemplified in the aforementioned patent.

In the machine of the mentioned patent, the stock is tensioned successively, in different locations along the edge of the bottom of the shoe, by means of gripper mechanism comprising a pair of jaws which, after closing on the lasting margin of the stock, draw the lasting margin inwardly from the edge of, and over, the shoe bottom, and the tensioned stock is pressed against the shoe bottom, in each location, by means of a presser feed foot which is also operable to feed the shoe, as well as by a feed retainer that serves to hold the shoe against retrograde movement during the back-feeding movement of the presser feed foot. In this prior mechanism, the gripper jaws are yieldingly closed on the lasting margin, through the action of a spring, and thereafter are positively moved to tension the stock which will slip through the yieldingly closed jaws when the pull exerted thereon exceeds the frictional grip of the jaws. As will be apparent, this frictional grip, which may be intentionally modified, to suit different operating conditions, by adjusting the tension of the gripper-closing spring, will also change with the thickness of the stock, the character of the surfaces of the stock engaged by the jaws as well as with the nature of the operating faces of these jaws. Thus, the amount of pull applied may vary, at different locations along the edge of the bottom of a shoe, as stock of different thicknesses or of different characters is encountered. Moreover, upon continued use it has been found that the operating surfaces of the gripper jaws, which in accordance with a usual practice would be roughened to enhance their frictional effect, sometimes become smoothed by the abrasive action of material in the stock so that their frictional grip is considerably lessened.

While the variation in the pull applied to the stock which may result from any of the above reasons is ordinarily not sufficient adversely to affect the lasting operation, it is desirable and preferable that the amount of pull applied be uniform at all locations along the edge of the bottom of the shoe. This is especially true in the

2

so-called platform cover-lasting operation where the pull applied to the cover by the gripper not only tensions the cover but also compresses the yieldable platform member somewhat. Under these conditions, a variation in the amount of pull may result in a corresponding variation in the thickness of the platform which would be visible in the completed shoe.

It is, therefore, an object of this invention to provide a novel and improved gripper mechanism by means of which a substantially uniform, yet selectively variable pull may be obtained. With this end in view, and in accordance with a feature of this invention, the herein illustrated gripper mechanism has a first jaw which is yieldingly movable in a direction to tension the stock, a second jaw which is reciprocated toward and away from the first jaw, and cooperating cam means associated with these jaws arranged to effect a relative closing movement of these jaws on the stock and, thereafter, movement of the first jaw by, and together with, the second jaw, in a direction to tension the stock. More particularly, these jaws each are provided with toothed operating faces so that when closed on the stock, by the action of the cam means, they grip it positively, regardless of the thickness or character of the stock, and, in accordance with a further feature of the invention, the second jaw is moved toward the first jaw through spring means, which are arranged to be adjusted to vary the amount of the pull applied, and is positively moved away from the first jaw. Also, and in accordance with a still further feature of the invention, means are provided for intermittently locking and unlocking the first jaw in time relation to the reciprocating movements of the second jaw so that the jaws, successively, grip, tension and release the stock during each reciprocation of the second jaw.

The above, and other, objects and features of the invention will be apparent from the following detailed description of the embodiment thereof, illustrated in the accompanying drawings, and will be pointed out in the claims.

In the drawings,

Fig. 1 is a view in side elevation of a lasting machine having gripper mechanism embodying the features of this invention;

Fig. 2 is a view similar to that of Fig. 1 but showing the gripper mechanism in a different position assumed during the operation of the machine;

Fig. 3 is a view in front elevation of a portion 55 of the machine shown in Fig. 1;

Fig. 4 is a view in front elevation and at an enlarged scale showing the operating elements only of the machine and with certain parts shown in section;

Fig. 5 is a section, on line V—V of Fig. 2, of a portion of the gripper mechanism; and

Figs. 6 and 7 are sectional views, taken on line VI—VI and line VII—VII of Fig. 2, respectively, and showing certain details of construction of the gripper mechanism.

Referring to the drawings, the improved gripper mechanism is therein illustrated as applied to a lasting machine which is similar to that disclosed in my aforementioned patent. The operating elements of this machine comprise a rear gripper jaw 10, a front gripper jaw 12, a combined shoe-bottom rest and lasting shield 14, a presser feed foot 16, a feed-retaining finger 18 and an edge gage roll 20. These various elements are supported on, and operated by mechanism contained within, a hollow head construction 22 having a lower portion 24 and an upper removable cover part 26. Inasmuch as the mechanisms for operating the presser feed foot 16 and feed-retaining finger 18 from a main power shaft 28, mounted in the head 22, is of no particular significance so far as the present invention is concerned and is fully disclosed and described in my prior patent, these mechanisms have been omitted from the drawings for the sake of clarity. Also, in Figs. 1 and 2 of the drawings, operating arms 16a and 18a which carry, respectively, the presser feed foot 16 and feed retainer 18, are shown partly broken away to avoid confusing the disclosure of the improved gripper mechanism. With the exception of the gripper mechanism, the herein illustrated machine operates in the same manner as the machine of my prior patent to tension the stock to be lasted, by drawing its lasting margin inwardly from the edge of the bottom of the shoe, to press the lasting margin of the tensioned stock against the shoe bottom and to feed the shoe.

In the machine illustrated in the drawings, the shoe-bottom rest 14 is mounted for movement to and from the operating position in which it is shown in the following manner. The shoe-bottom rest is secured, by screws 30, to the lower end of a lever 31 which is rotatably mounted on a cross shaft 32 carried by a forwardly projecting portion of the cover 26. At its upper end, this arm is adjustably secured, by means of a screw 34 and slot 36, to an arm 38 which is likewise rotatably mounted on the shaft 32, and connected to this arm is a link 40 which is pinned to the end of a rocker arm 42 secured to a shaft 44. Also secured to the shaft 44, outside of the cover 26, is a second rocker arm 46 to which is connected a treadle rod 48. In Figs. 1 and 2 of the drawings, this treadle rod is shown as lowered, against the action of a spring, not shown, so as to straighten the toggle formed by the link 40 and the rocker arm 42 thereby to swing the lever 38 in a counterclockwise direction and move the shoe-bottom rest 14 to its operating position as shown. When the treadle, not shown, is released, the rod 48 will be elevated by the spring, also not shown, and the toggle broken, thus swinging the lever 38 in a clockwise direction and shifting the shoe-bottom rest to its inoperative position.

Referring now to the gripper mechanism with which this invention is concerned, the rear gripper jaw 10 is carried by an elongated arm 50 which is pivotally connected to the left-hand end

of a rod 52. This rod is slidable in guideways 54, 56 formed in upstanding portions 58, 60 rising from a carrier 62. At its right-hand end, this rod is clamped, by means of a screw 66, to a block 64 which at its upper portion is provided with an ear 68, see Fig. 7. This ear is confined within a slot 70, formed on a rearwardly projecting part of the upstanding portion 60, so as to prevent rotation of the rod 52 while permitting this rod to slide longitudinally in the guideways 54, 56. Passing through the block 64, and positioned on opposite sides of the upstanding portion 60, are two rods 74, 74, see Fig. 7. Each of these rods has a rearwardly and downwardly inclined end portion 76, see Figs. 1 and 2, and each rod is secured to the block 64 by means of a setscrew 78. The rods 52 and 74 also pass through and support a block of cushioning material 69 which is interposed between the upstanding portion 60 and the block 64.

The rod 52 is urged yieldingly and to the left, relatively to the carrier 62, by means of a pair of tension springs 80, 80, see Fig. 6, each of these springs being stretched between the downturned end 76 of one of the rods 74 and an adjustable anchor block 82, see Figs. 1, 2 and 6. This anchor block has a bifurcated upper end which embraces a crossbar 84, extending between the upstanding portions 58 and 60 and secured to the latter by a screw 86, and a lower end which is slotted at 88 to straddle the rod 52, see Fig. 6. Secured to the block 82 is a threaded stud 90 which extends to the left, as viewed in Figs. 1 and 2, and through a clearance hole 92 formed in the upstanding portion 58. Threaded on to this stud is an adjusting sleeve 94 which has an enlarged end 96 adapted to seat on a shoulder 98 formed in the hole 92. The sleeve 94 is provided with a slot 100 for receiving a screw driver, or other suitable tool, for rotating the sleeve to shift the anchor block 82 to the right or to the left, thereby decreasing or increasing the tension of the springs 80. The upstanding portion 60 limits movement of the block 82 to the right end, to prevent the sleeve 94 from being wholly unscrewed from the stud 90 after this limit of movement of the anchor block 82 has been reached, a stop 102, secured to the crossbar 84 by means of a screw 104, is arranged to engage the enlarged portion 96 on the sleeve 94.

The carrier 62 is supported on two rocker arms 110, 112 and during the operation of the machine is reciprocated by means of an eccentric 114, carried by the main shaft 28, the motion of which is transmitted to the rocker arm 112 by means of a connecting rod 116 and a third rocker arm 118 which is connected to the rocker arm 112. As will be apparent by reference to the above-mentioned patent, the above arrangement for supporting and reciprocating the carrier 62 of the herein illustrated machine is similar to that provided in the machine of the patent for supporting and reciprocating the carrier 32.

The arm 38 is provided with a depending lug 130 and a rearwardly extending shoulder 132. Pivotedly supported on the lug 130, by means of a pin 134, is an angular lever 136 having a forwardly and downwardly extending arm 138, a rearwardly extending portion 140 and a flat abutment surface 142. A coil spring 144, stretched between the arm 38 and the rearwardly extending portion 140, tends to hold the lever 136 in the position in which it is shown in Fig. 1, and with the abutment surface 142 pressed against a block 146 of cushioning material such, for example, as rubber or leather which is fitted into a dovetail re-

cess formed in the shoulder 132. The front gripper jaw 12 has an upturned portion 148 which fits snugly between two ears 150, 152 formed on the arm 138 of the lever 130, and beneath a pin 154 which passes through these two ears, see Fig. 3. The upper end of the portion 148 of the front gripper jaw is slotted at 156 to receive a clamping screw 158. When this clamping screw is loosened, the front gripper jaw may be adjusted vertically with respect to the rear gripper jaw 10 in a manner which should be readily apparent.

Pivots connected to the arm 138, by means of a pin 160 and clevis block 162, is a locking rod 164. This rod extends rearwardly of the machine and passes through clearance holes 166, 168 formed in the upstanding portions 58 and 60, respectively, the hole 88 in the block 82, a clearance hole 170 in the block 64 and between two locking blocks 172, 174. These two locking blocks are fitted in a recess 175 of a housing 176, which projects upwardly from a web 178 formed integrally with the lower head portion 24, and are grooved at 180, 182, see Fig. 5, to receive the locking rod 164. The blocks 172, 174 are supported on an eccentric 184 which is formed integrally with a lever 186, this eccentric engaging a recess 187 in the lower block 174. The upper block 172 is urged downwardly by an adjusting screw 193, threaded through the housing 176, and is held against longitudinal movement, relatively to the housing, by means of flanges 188, 190 thereon.

The lever 186 is rotatably mounted on a pin 191 and has a cam portion 192 which, at times, is adapted to be engaged by a roll 194 toward which the lever 186 is swung by means of a coil spring 196. This coil spring is stretched between a pin 198, carried by the lever 186 and a bracket 200 which is supported on a pin 202, carried by the housing, and held against rotation under the pull of the spring by engagement with the pin 191. The roll 194 is mounted on a bell-crank lever 204 which is oscillated from the eccentric 114 by means of a connecting rod 206, a rocker arm 208 and a link 210. The rod 164 also extends through a notch 212, cut in an upwardly extending projection 214 on the lever 186 and is provided with a threaded end for receiving a nut 216.

Journaled on a stud 220, carried by the lever 136, is a grooved roll 222 which is directly in line with the rear gripper jaw 10. This jaw has an inclined portion facing the roll which is provided with a rib 224 adapted to cooperate with this grooved roll when the rear jaw is advanced toward the front jaw by the reciprocation of the carrier 62. As shown in Fig. 1, when the rear jaw is withdrawn from the front jaw, the arm 50 is elevated by means of a leaf spring 228 to the extent permitted by the engagement of the rear jaw with a flat surface 230 formed on the lower side of the clevis block 162.

The operation of the gripper mechanism will now be described. Referring to Fig. 1, the carrier 62 is in its extreme limit of movement to the right and the rear gripper jaw 10 is separated from the front gripper jaw 12 as shown. Also, the lever 186 has been rotated, in a counterclockwise direction by the engagement of the roll 194 with a portion of the cam surface 192 so as to relieve the clamping pressure of the eccentric 184 on the blocks 172, 174 thus releasing the rod 164 and permitting spring 144 to swing the lever 136 in a counterclockwise direction until surface 142 bears against the cushioning block 146. Inasmuch as the treadle (not shown) is now depressed, the front gripper jaw 12 will be yieldingly held in the

position shown in Fig. 1 by the spring 144. As the shaft 28 rotates, in the direction of the arrow, the carrier 62 will be moved to the left and with it the rear gripper jaw 10. When the inclined ridge 224, on the rear gripper jaw, engages the roll 222, the rear jaw 10 will be cammed downwardly, the spring 144 being effective to hold the lever 136 against rotation about the pin 134, until the lasting margin of the stock, herein illustrated as the cover C of a slip-lasted shoe comprising a platform P and upper U, assembled on the last L, is firmly gripped between the operating faces of the two jaws 10 and 12. Preferably, and as herein illustrated, the operating faces of these two jaws are provided, respectively, with intermeshing teeth 231, 232 to augment their gripping action. Accordingly, and as a result of the relative approaching movement of the operating faces of the jaws 10 and 12, caused by the camming effect of the inclined rib 224 on the roll 222, the lasting margin of the cover C will be seized with a positive, non-slipping grip.

As the carrier 62 continues its movement to the left, after the lasting margin of the cover C has been gripped by the jaws 10 and 12 in the manner explained above, the spring 144 yields, thus permitting the lever 136 to rotate in a clockwise direction about the pin 134. Accordingly, the two jaws 10 and 12 now move together, as a unit and to the left, to tension the cover by drawing its lasting margin inwardly from the edge of the bottom of the platform P and over the shoe-bottom rest 14. Fig. 2 shows the operating parts of the machine in the positions assumed at the completion of the tensioning action and after the shaft 28 has rotated 180° from the position shown in Fig. 1. The amount of tension applied to the cover C by the gripper jaws 10 and 12 is determined by the springs 80 through which movement of the carrier to the left is transmitted to the rod 52 and to the arm 50 which carries the jaw 10. Therefore, when this predetermined amount of tension has been applied, these springs will yield and movement of the jaw 10 will be terminated, the block 64 now separating from the cushioning block 69, in the manner shown in Fig. 2, in response to the continued movement of the carrier 62.

As the shaft 28 continues to turn, the bell-crank lever 204 is rotated in a counterclockwise direction to cause the roll 194 to travel along the cam surface 192 to a position thereon in which the spring 196 can turn the lever 186 in a clockwise direction so that the eccentric 184 will be effective to apply clamping pressure on the rod 164 through the blocks 172, 174. With this rod thus locked, the lever 136 is held against movement by the spring 144 so that the front jaw 12 is held in the position in which it is shown in Fig. 2 as the rear jaw is moved reversely to release the cover C during the return reciprocation of the carrier 62. Just as this return reciprocation of the carrier is completed, the roll 194 again assumes a position on the cam surface 192 in which the lever 186 is turned so as to relieve the clamping pressure of the blocks 172, 174 on the rod 164. With this rod thus unlocked, spring 144 swings the lever 136 back to the position in which surface 142 thereon bears against the cushioning block 146, as shown in Fig. 1.

From the above, it will be seen that in each cycle of operation of the gripper mechanism, effected by a complete reciprocation of the carrier 62 and jaw 10, the jaws 10 and 12 are first closed to grip the cover C firmly, then moved

together, and as a unit, to apply a yielding pull of an amount determined by the springs 80 and finally separated to release the stock after it has been tensioned. As in my prior machine, just before the gripper jaws are separated to release the stock, the lasting margin thereof is pressed against the shoe bottom, i. e., the platform P, by the presser feed foot 16 which thereafter moves to feed the shoe to present the next succeeding portion of the cover to the action of the grippers. Also the feed-retaining finger 18 operates to hold the shoe against retrograde movement during the back-feeding motion of the presser-feed foot.

When the treadle is released and the toggle formed by link 40 and rocker arm 42 broken, arm 38 and lever 34 will be rotated in a clockwise direction to move the shoe bottom rest 14 outwardly and upwardly to its inoperative position. During this movement of the arm 38, the cushioning block 146 will engage the surface 142 on the lever 136 and, when the rod 164 has been unlocked, this lever will move with the arm 38, thus shifting the jaw 12 and cam roll 222 beyond the range of movement of the jaw 10. The nut 216, threaded on the rod 164, is so positioned, when the treadle is released and the arm 38 and lever 136 moved together in the above manner, as to engage the lever 136 and swing it, in a counterclockwise direction, sufficiently to hold the cam surface 192 separated from the roll 194. Thus, wearing of this cam surface, as well as of the eccentric 184, while the machine is permitted to run idly, is avoided.

Having described the invention, what I claim as new and desire to secure by Letters Patent of the United States is:

1. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw toward and away from said first jaw, and cooperating means associated with said jaws constructed and arranged, upon movement of the second jaw in a direction toward the first jaw, to effect relative approaching movement of said operating faces for gripping the lasting margin and, thereafter, to cause movement of said first jaw by, and together with, said second jaw, for tensioning the stock.

2. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw toward and away from said first jaw, and cooperating cam means associated with said jaws constructed and arranged, upon movement of the second jaw in a direction toward the first jaw, to effect relative approaching movement of said operating faces for gripping the lasting margin and, thereafter, to cause movement of said first jaw by, and together with, said second jaw for tensioning the stock.

3. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw toward and

away from said first jaw, cooperating means associated with said jaws constructed and arranged, upon movement of the second jaw in a direction toward the first jaw, to effect relative approaching movement of said operating surfaces for gripping the lasting margin and, thereafter, to cause movement of said first jaw by, and together with, said second jaw in a direction to tension the stock, and means associated with said first jaw for preventing retrograde movement thereof during reciprocation of said second jaw in the opposite direction, thereby to release the stock after it has been thus tensioned.

4. A gripper mechanism comprising a first jaw, 15 yieldingly movable in a direction to tension the stock and having an operating face for engaging one side of the lasting margin of the stock, a second jaw having an operating face for engaging the opposite side of the lasting margin, means 20 for reciprocating said second jaw toward and away from said first jaw, cooperating cam means associated with said jaws constructed and arranged, upon movement of the second jaw in a direction toward the first jaw, to effect relative 25 approaching movement of said operating surfaces for gripping the lasting margin, and, thereafter, to cause movement of said first jaw by, and together with, said second jaw in a direction to tension the stock, and means associated with said first 30 jaw for preventing retrograde movement thereof during reciprocation of said second jaw in the opposite direction, thereby to release the stock after it has been thus tensioned.

5. A gripper mechanism comprising a first jaw, 35 yieldingly movable in a direction to tension the stock and having an operating face for engaging one side of the lasting margin of the stock, a second jaw having an operating face for engaging the opposite side of the lasting margin, means for 40 reciprocating said second jaw toward and away from said first jaw, cooperating means associated with said jaws constructed and arranged, upon movement of the second jaw in a direction toward the first jaw, to effect relative approaching movement of said operating surfaces for gripping the lasting margin and, thereafter, to cause movement of said first jaw by, and together with, said second jaw in a direction to tension the stock, and means for intermittently locking and unlocking 45 said first jaw in time relation to the reciprocating movements of said second jaw, thereby to cause said jaws successively to grip, tension and release the stock during each reciprocation of said first jaw.

6. A gripper mechanism comprising a first jaw, 55 yieldingly movable in a direction to tension the stock and having an operating face for engaging one side of the lasting margin of the stock, a second jaw having an operating face for engaging 60 the opposite side of the lasting margin, means for reciprocating said second jaw toward and away from said first jaw, cooperating cam means associated with said jaws constructed and arranged, upon movement of the second jaw in a direction 65 toward the first jaw, to effect relative approaching movement of said operating surfaces for gripping the lasting margin, and, thereafter, to cause movement of said first jaw by, and together with, said second jaw in a direction to tension the stock, and means for intermittently locking and 70 unlocking said first jaw in time relation to the reciprocating movements of said second jaw, thereby to cause said jaws successively to grip, tension and release the stock during each reciprocation of said first jaw.

7. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw yieldingly toward and positively away from said first jaw, and cooperating means associated with said jaws constructed and arranged, upon movement of the second jaw in a direction toward the first jaw, to effect relative approaching movement of said operating faces for gripping the lasting margin and, thereafter, to cause movement of said first jaw by, and together with, said second jaw for tensioning the stock.

8. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw yieldingly toward and positively away from said first jaw, and cooperating cam means associated with said jaws constructed and arranged, upon movement of the second jaw in a direction toward the first jaw to effect relative approaching movement of said operating faces for gripping the lasting margin and, thereafter, to cause movement of said first jaw by, and together with, said second jaw for tensioning the stock.

9. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw including adjustable spring means for moving said second jaw toward said first jaw and positive means for moving said second jaw away from said first jaw, and cooperating means associated with said jaws constructed and arranged, upon movement of the second jaw in a direction toward the first jaw, to effect relative approaching movement of said operating faces for gripping the lasting margin and, thereafter, to cause movement of said first jaw by, and together with, said second jaw for tensioning the stock.

10. A gripper mechanism comprising a first jaw, yieldingly movable in a direction to tension the stock and having an operating face for engaging one side of the lasting margin of the stock, a second jaw having an operating face for engaging the opposite side of the lasting margin, means for reciprocating said second jaw including adjustable spring means for moving said second jaw toward said first jaw and positive means for moving said second jaw away from said first jaw, and cooperating cam means associated with said jaws constructed and arranged, upon movement of the second jaw in a direction toward the first jaw, to effect relative approaching movement of said operating faces for gripping the lasting margin and, thereafter, to cause movement of said first jaw by, and together with, said second jaw for tensioning the stock.

11. A gripper mechanism comprising a first jaw yieldingly movable in a direction to tension the stock and having a toothed operating face for engaging one side of the lasting margin of the stock, a second jaw having a toothed operating face for engaging the opposite side of the lasting margin, means for reciprocating said second jaw

65

70

toward and away from said first jaw, and cooperating means associated with said jaws constructed and arranged, upon movement of the second jaw in a direction toward the first jaw, to effect relative approaching movement of said operating faces for positively gripping the lasting margin and, thereafter, to cause movement of said first jaw by, and together with, said second jaw, for tensioning the stock.

12. A gripper mechanism comprising a first jaw yieldingly movable in a direction to tension the stock and having a toothed operating face for engaging one side of the lasting margin of the stock, a second jaw having a toothed operating face for engaging the opposite side of the lasting margin, means for reciprocating said second jaw toward and away from said first jaw, and cooperating cam means associated with said jaws constructed and arranged, upon movement of the second jaw in a direction toward the first jaw, to effect relative approaching movement of said operating faces for positively gripping the lasting margin and, thereafter, to cause movement of said first jaw by, and together with, said second jaw, for tensioning the stock.

13. A gripper mechanism comprising a first jaw yieldingly movable in a direction to tension the stock and having a toothed operating face for engaging one side of the lasting margin of the stock, a second jaw having a toothed operating face for engaging the opposite side of the lasting margin, means for reciprocating said second jaw including adjustable spring means for moving said second jaw toward said first jaw and positive means for moving said second jaw away from said first jaw, and cooperating means associated with said jaws constructed and arranged, upon movement of the second jaw in a direction toward the first jaw, to effect relative approaching movement of said operating faces for positively gripping the lasting margin and, thereafter, to cause movement of said first jaw by, and together with, said second jaw for tensioning the stock.

14. A gripper mechanism comprising a first jaw yieldingly movable in a direction to tension the stock and having a toothed operating face for engaging one side of the lasting margin of the stock, a second jaw having a toothed operating face for engaging the opposite side of the lasting margin, means for reciprocating said second jaw including adjustable spring means for moving said second jaw toward said first jaw, and positive means for moving said second jaw away from said first jaw, and cooperating cam means associated with said jaws constructed and arranged, upon movement of the second jaw in a direction toward the first jaw, to effect relative approaching movement of said operating faces for positively gripping the lasting margin and, thereafter, to cause movement of said first jaw by, and together with, said second jaw for tensioning the stock.

JOSEPH FOSSA.
